UNITED STATES PATENT OFFICE.

CHARLES THOMA, JR., OF CARLSTADT, NEW JERSEY.

MUSIC-LEAF TURNER.

SPECIFICATION forming part of Letters Patent No. 757,979, dated April 19, 1904.

Application filed January 4, 1904. Serial No. 187,618. (No model.)

To all whom it may concern:

Be it known that I, CHARLES THOMA, Jr., a citizen of the United States, and a resident of Carlstadt, in the county of Bergen and State 5 of New Jersey, have invented a new and Improved Music-Leaf Turner, of which the following is a full, clear, and exact description.

The purpose of my invention is to provide a simple, light, durable, and economic construction of music-leaf turner and one which will not injure the sheet or page of music in connection with which it is used, and, further, to provide a conveniently - accessible means for turning one leaf after the other, each leaf being independently turned by a single movement of the hand, which movement will necessitate the removal of the hand from the keyboard for only a fractional portion of a second of time.

20 A further purpose of the invention is to provide a construction wherein a single releasing device is in operative connection with all of the leaf-turning arms and wherein each leaf-turning arm is provided with an independent lock or latch lever, the releasing mechanism for each succeeding lock or latch lever being set in position for operation as the preceding music-carrying arm is released.

25 Another purpose of the invention is to provide a device of the character described which will take up but little room and which will not necessarily mar the finest polished surface acting as its support and which includes a stand serving as a bearing for the music-sheets to lean against.

The invention consists in the novel construction and combination of the several parts, as will be hereinafter fully set forth, and pointed out in the claims.

40 Reference is to be had to the accompanying drawings, forming a part of this specification, in which similar characters of reference indicate corresponding parts in all the figures.

45 Figure 1 is a front elevation of the improved music-leaf turner, showing a part of a sheet of music carried thereby, a portion of the music-leaf turner being in section. Fig. 2 is a front elevation of the music-leaf turner with

the front or cover plate removed, disclosing the operative parts of the device. Fig. 3 is 50 a horizontal section looking upward, which section is taken practically on the line 3-3 of Fig. 2; and Fig. 4 is an end view of the device, the music-carrying arms being shown in transverse section.

55 The body A of the device is in the form of a box-casing comprising a back member 10, an upper longitudinal forwardly-extending member 11, the ends 11^a whereof preferably extend beyond the ends of the body proper, 60 and a bottom longitudinal member 12, the terminal portions 12^a whereof are shown as being bent downward and outward to form legs, and these legs may be covered with felt or other soft material, if desired. The body 65 of the casing is substantially completed in construction by the addition of a front cover-plate 14, (shown in Figs. 1 and 4,) and it may be here remarked that the ends of the body may be closed by suitable plates a, as shown 70 in Fig. 4, or the end portions of the said body may be left open.

75 At the front upper and lower central portion of the body A forwardly-extending horizontally - disposed segmental lugs 13 are formed, and the front plate 14 is provided with a central correspondingly segmentally formed section 15, and in this segmental section of the said front plate 14 slots 16 are made extending longitudinally of the plate. These 80 slots may be in any desired number, but they should correspond in number to the number of leaf - turning arms E employed. Longitudinal grooves or depressions 17 are made in the outer face of the front plate 14, ex- 85 tending one from the left-hand end of each slot 16 to the left-hand terminal of the said plate, and corresponding slots 17^a are made at the right-hand portion of the said front plate 14, and at one side edge of the latter 90 slots 17^a recesses 18 are produced, a recess 18 being provided for each slot 17^a. A pivot- 95 pin 19 is made to extend through the lugs 13 of the body A, the said pivot-pin being fixed to the said lugs.

Near the left - hand end of the body A a

keeper-plate 20 is secured to the inner face of the back 10, and the right-hand end portion 21 of this keeper-plate 20 is more or less outwardly arched and extends in direction of 5 the right-hand end of the body, as is shown best in Fig. 3.

Adjacent to the keeper-plate 20 a releasing-plate B is located on the inner face of the back member 10 of the body. This releasing-plate B is arched or curved at its left-hand end, and the left-hand end portion of the said plate has direct bearing on the inner face of 10 the back member 10 of the body, as is also best shown in Fig. 3. The left-hand end of 15 the body portion 23 of this releasing-plate B is flat and substantially rectangular, being provided with a transverse slot 24, as is shown in both Figs. 2 and 3. Where the curved section 22 of the said releasing-plate B connects 20 with the body or flat section 23 a trough 25 is produced in the forward face of the said releasing-plate, the trough being rectangular or polygonal in cross-section. The polygonal or rectangular section 26 of an angular trip-arm C is made to fit in the trough 25, as is shown also in Fig. 3, which angular trip-arm C comprises a vertical member c' and a horizontal member c. The vertical member c' of the trip-arm C is pivoted in the top and 25 bottom portions of the body A of the device in a manner which will enable the said member c' to turn, the polygonal portion 26 of the trip-arm being between the upper and lower pivots of the said section c'. The lower or 30 horizontal section c of the trip-arm extends forwardly beyond the forward edge of the body A at a desired point below its bottom portion and beneath an angular bracket D, which extends from the central bottom portion 35 of the said body A at the front.

When a music-turning arm E is to be released from its locking device, to be herein-after described, and automatically carried, by means also to be herein-after described, from 40 the right-hand portion of the body to the left-hand portion of the body, the locking device is released through the medium of the outward movement of the flat or body portion 23 of the releasing-plate, and when the plate is 45 moved to accomplish such a result the slotted end of the plate moves forwardly from the back of the body and the curved portion 22 of the said releasing-plate is forcibly pressed against the back member 10 of the body, and 50 so acts as a spring to return the plate to its normal position when relieved from tension. This movement of the releasing-plate B is brought about by turning the aforesaid angular trip-arm C, and such movement is ac- 55 complished by means of a shifting device consisting of a finger-piece D', having sliding movement in the bracket D, which finger-piece within the bracket is pivoted to one ex-

tremity of an elbow-lever 27, fulcrumed in the bracket D, as is shown in Fig. 1, the terminal of the other member of the said elbow-lever 27 being preferably curved, so as to have a bearing against a side of the lower or horizontal member c of the aforesaid trip-arm C. Therefore by quickly pulling down 65 the finger-piece D' the trip-arm C is rocked and the releasing-plate B is given the movement just above mentioned. It may be here remarked that the body is shown as braced at a point back of the plate 14 by means of a cross-bar 22^a, and any desired number of such may be employed.

I have illustrated four sheet or leaf turning arms E in position in the body. These arms extend longitudinally of the body and are 80 preferably graduated as to length, the graduation being such that the upper arm is the shortest and the lower arm is the longest. Each sheet or leaf turning arm is attached to a drum e, and these drums, as is best shown 85 in Fig. 2, are mounted to turn on the pivot-pin 19. A spring 28 is coiled around each drum, one end of each spring being secured to a drum, and the opposite ends of the said springs are secured to the arched portion 21 of the 90 keeper-plate 20, as is illustrated at 29 in Figs. 2 and 3, and the drums are preferably grooved to receive the springs, in consequence of which construction only a portion of a spring appears in Fig. 3. These springs have a tendency to 95 draw the sheet or leaf turning arms E over to the left-hand side portion of the body, and these springs are placed under tension when the sheet or leaf turning arms are at the right-hand portion of the body A, and consequently locking devices are needed to hold the said sheet or leaf turning arms E in their latter position. Each sheet or leaf turning arm E is provided with a hook-shaped keeper 30, which extends rearward from what is the rear edge of an arm 105 E when the arm is over at the right of the body, as is illustrated in Fig. 3. In connection with each keeper 30 a latch-lever is employed. These latch-levers, reading from the top downward, are designated, respectively, 110 as 31, 32, 33, and 34 and are suitably pivoted on the back of the body near the left-hand end thereof, as is shown in Figs. 2 and 3. Each latch-lever is provided with a suitable head 35, adapted to engage with a keeper 30 115 on a leaf or sheet turning arm E. The upper latch-lever 31 is shorter than the others, all of the others being of the same length, and the inner end of this upper or shorter latch-lever 31 rests normally upon the front face of the 120 releasing-plate B at a point above and to the right of the slot 24 in the said plate, whereas the inner ends of all of the other latch-levers extend normally over the aforesaid slot 24 in the releasing-plate B. The inner ends of the latch-levers are normally pressed rearward by means 125

of spring-tongues 36, having bearing against the right-hand ends of the levers, as is shown in Figs. 2 and 3, the said tongues usually extending from a bar 37 on which the latch-levers are pivoted. A lifting-arm 38 is connected with each drum *e*, with the exception of the lowermost drum, and these lifting-arms extend from the drums in direction of the right-hand end of the body *A*, having their left-hand ends outwardly curved and eccentrically and pivotally mounted on the drums by suitable pins 39, as is shown in Fig. 3.

At the front or right-hand end of each lifting-arm 38 a shoe 40 is formed, apertured for the free passage of the longer or left-hand end of a latch-lever—namely, the latch-levers 32, 33, and 34—as is shown in Figs. 2 and 3, and when the sheet or leaf turning arms *E* are carried to the right and are held by the heads of the latch-levers all the shoes 40 of the lifting-arms 38 will be over the slot 24 in the releasing-plate *B*, as is shown in Fig. 2. Each sheet or leaf turning arm *E* at its free end has pivotally attached to it a finger 41, and these fingers are adapted to be placed between the leaves or sheets of music to be turned, and at the upper portion of the body *A* a frame 42, usually in the form of a lyre, is secured in any suitable manner, upon which the music has bearing between its upper and lower edges; but the lower edge of the music will rest upon the upper member 11 of the body *A*, having the end extensions 11^a. The said body *A* has bearing upon the music-supporting ledge of a piano, organ, or a music-stand, for example.

In operation after the device has been set, as is shown in Figs. 1 and 2, and after the music on the first leaf or sheet has been played the finger-piece *D'* is drawn down by a quick movement of the hand, whereupon the slotted end of the releasing-plate *B* is carried outward, and consequently the upper latch-lever 31, which action releases the upper sheet-turning arm *E*, whereupon its spring 28 acts to carry the arm over to the left and turn the sheet with which the finger 41 of the arm engages. When the upper sheet-turning arm is in position at the left of the body, the shoe of the uppermost lifting-arm 38 will have been carried over the releasing-plate at its right-hand end, while the shoes of the other arms will remain stationary over the slot 24 in the said releasing-plate. Therefore when the finger-piece *D'* of the shifting device is again drawn down the shoe upon the lifting-arm 38, connected with the latch-lever 32, will be carried outward by the right-hand end portion of the releasing-plate *B* and will release the latch-lever 32 from engagement with the second upper sheet-turning arm, whose spring 28 will then act to throw said arm to the left, and as the said arm so turns it will place the shoe 40 of the next lifting-arm 38 in position

to lift the third turning-arm *E* when the finger-piece *D'* is next operated, and so on. 65

Having thus described my invention, I claim as new and desire to secure by Letters Patent—

1. In music-leaf turners, pivoted, spring-controlled sheet-turning arms, spring-controlled latch-levers for the turning-arms, a release device for the latch-levers, an operating mechanism for the releasing device, and arms for establishing operative relation between the releasing device and the latch-levers, said arms being placed in position by the throw of 75 the turning-arms.

2. In music-leaf turners, pivoted spring-controlled latch-levers for the turning-arms, actuating-arms for the latch-levers, connections whereby the actuating-arms are thrown into 80 operative position by the throw of the turning-arms, a releasing-plate arranged for movement at the rear of the actuating-arms, the said plate being provided with an opening, shoes extending from the actuating-arms, 85 having sliding connection with the latch-levers, and a shifting mechanism for the releasing-plate, as described.

3. In music-leaf turners, pivoted spring-controlled sheet-turning arms, spring-controlled 90 latch-levers for the turning-arms, actuating-arms for the latch-levers, having sliding connection therewith and pivotal connection with the turning-arms, a releasing-plate having an opening therein located at the rear of the latch-levers and the actuating-arms, said plate being provided with an arched spring-section at 95 one end, the remaining portion of the plate being flat, and a trip-arm connected with the releasing-plate, as set forth. 100

4. In music-leaf turners, pivoted spring-controlled sheet-turning arms, spring-controlled latch-levers for the turning-arms, actuating-arms for the latch-levers, having sliding connection therewith and pivotal connection with the turning-arms, a releasing-plate having an opening therein located at the rear of the latch-levers and the lifting-arms, the said plate being provided with an arched spring-section at 105 one end, the remaining portion of the plate being flat, a trip-arm connected with the said releasing-plate, a finger-piece, a guide for the finger-piece, and an elbow-lever connected with the said finger-piece and having operative bearing upon the said trip-arm, as set 110 forth. 115

5. In a music-leaf turner, a box-casing, a fixed shaft in the said casing, sheet-turning arms pivoted on the said shaft, each arm at its pivotal portion being provided with a drum, 120 springs attached to the drum and to the casing, spring-controlled latch-levers for the said turning-arms, pivoted on the said casing, actuating-arms having sliding connection with the latch-levers and eccentric connection with 125 the drums forming a portion of the turning-

arms, a releasing-plate for the actuating-arms, and a shifting device located partially at the forward portion of the casing and partially within the casing, which shifting device has 5 operative connection with the said releasing-plate, for the purpose described.

In testimony whereof I have signed my name

to this specification in the presence of two subscribing witnesses.
